J. T. King

Washing Machine,

No 8446.

Patented Oct. 21, 1851.

UNITED STATES PATENT OFFICE.

JAMES T. KING, OF BALTIMORE, MARYLAND.

WASHING APPARATUS.

Specification forming part of Letters Patent No. 8,446, dated October 21, 1851; Reissued April 13, 1852, No. 215.

To all whom it may concern:

Be it known that I, JAMES T. KING, of Baltimore, in the State of Maryland, have invented a new and useful Apparatus for 5 Washing and Cleansing Clothes, Called "James T. King's Washing Apparatus"; and I do hereby declare that the following is a full, clear, and exact description of the construction of the same, reference being had to the annexed drawings.

Figure 1 represents a perspective view of the front end and side next to the flue. Fig. 2 represents a perspective view of the back end and front side without the top boiler. 15 Fig. 3 represents a longitudinal section. Fig. 4 represents the hearth of the furnace. Fig. 5 represents a cap to place over the revolving boiler in place of top boiler to complete the flue. Fig. 6 represents a front 20 view of the pipe inside of revolving boiler. Fig. 7 represents a frame covered with felt or any other suitable substance to be placed in door frame to make the door tight. Fig. 25 Fig. 8 represents pipe and coupling joint to be screwed on pipe D without top boiler. Fig. 9 represents the front end of the furnace constructed of brick.

The same letters in all cases represent like parts.

30 a is a revolving boiler the circumference of its heads projecting sufficient to cover the space between it and the edge of top boiler or cap.

b is plate with projections for the axis of 35 boiler and packing chamber.

C is packing box by which the space between pipe D and the axis of boiler is made tight.

D is pipe extending through the axis of 40 boiler a and upon the inside held stationary by a brace from frame i through which pipe the boiler is filled with water and the steam allowed to escape either while the boiler is revolving or stationary.

45 E is projection on inside of revolving boiler by which the position of the clothes are changed every revolution of the boiler. These projections may be made in any manner best suited to the purpose.

50 F is pipe with coupling joint to connect it with pipe (D). This pipe may extend over and into boiler (H) through coupling joint g, which allows the end of said pipe

to turn into either side of boiler H or if cap (5) is used instead of boiler (H) the tube 55 No. (8) may be used instead of pipe f. After supplying boiler (a) with water through it, it may be turned downward to let the water out of pipe (d) and the steam from the boiler.

60 H, is boiler placed over boiler (a) resting upon frame (i) the sides of said boiler projecting below its bottom sufficient to form the upper half of flue (m). This boiler is constructed with pipes extending from both 65 sides to pipe (F) through which boiler (A) is supplied with water by turning stop cock (j).

I is frame which supports the boilers resting upon and held fast to side plates of furnace by screw there being a small projection on the inside of side plates similar to those on the frame.

K is faucet connected with pipe (F) by which the water may be let out of pipes 75 after supplying boiler (a) and by which the water may be drained from boiler (H).

L is partition in boiler (H).

M is space between boilers (a) and (H) 80 constituting flue by which both boilers are heated by the same fire.

N is pipe to conduct smoke from the flue (M).

O is smoke pipe with damper in it by which the fire is conducted away from the 85 boilers. The dotted lines over said pipe represent large damper by which the fire is entirely shut off from the boilers, this damper rests on a flange on the inside of each end plate of furnace, said damper connected with rod (q) running through front side of furnace by which said damper is moved.

90 R is damper which shuts off the direct draft to pipe (N) and causes the draft to surround boiler (a).

S is door held fast by screws or springs, made tight by frame (7). By this door articles are put in and taken out of boiler.

T is half round plate with projections for axis and handle.

100 U is handle and crank by which boiler (a) is revolved.

V is faucet by which the water is drained from boiler (a) or when turned upward it may be used for letting off surplus steam before loosening the door.

W is flange riveted on the furnace under boiler (a) by which water is conducted into gutter (x).

x is gutter used for conducting off the 5 dirty water from boiler (a).

Y is tub to contain the clothes direct from the boiler.

Z is door of furnace.

That the purposes for which this apparatus is intended and its good qualities may be more fully understood I will explain its operations as follows. Fill boiler (H) with water and boiler (a) about half full, shut the door tight, and build fire in furnace as soon as steam begins to escape from boiler (a) put in sufficient soap or any washing preparation to make a good suds give the boiler a few turns then put in your clothes fasten the door tight let them stay in from 15 3 to 20 minutes turning the boiler occasionally the time depending upon the strength of the suds the heat the turning and the nature of the clothes. If the clothes are not very much soiled two or three lots 20 25 may be washed in the same suds. As soon as this suds is dirty let it off first having shut the damper over the fire then let in

hot water from boiler (H) resupply boiler (H) and go on as before. By this operation one person (with an apparatus the revolving boiler of which is two feet long by two feet diameter with its appurtenances) will do as much washing as 12 persons can do by hand in the same time and with less expense for fuel soap, &c.

Having thus fully described my invention what I claim therein as new and desire to secure by Letters Patent is—

The application of boiler (h) with or without divisions, placed over the revolving boiler resting on frame (i) the bottom of which boiler forms the upper half of the flue (m) by which both boilers are heated by the same fire, and from which the revolving boiler may be supplied with water, 45 as herein fully described and represented.

In witness whereof I have hereunto subscribed my name the tenth day of June eighteen hundred and fifty one.

JAMES T. KING.

In presence of—

J. D. CLARK,

R. C. JOHNSON.

[FIRST PRINTED 1913.]
